UNITED STATES PATENT OFFICE.

CARL G. PRITCHARD, OF WARREN, OHIO, ASSIGNOR TO THE HARRIS AUTOMATIC PRESS COMPANY, OF NILES, OHIO, A CORPORATION OF OHIO.

PRINTING-PRESS.

1,113,483.

Specification of Letters Patent. Patented Oct. 13, 1914.

Application filed October 18, 1912. Serial No. 726,530.

To all whom it may concern:

Be it known that I, CARL G. PRITCHARD, of Warren, in the county of Trumbull and State of Ohio, have invented certain new and useful Improvements in Printing-Presses; and I do hereby declare the following to be a full, clear, and exact description of the invention, such as will enable others skilled in the art to which it appertains to make and use the same.

This invention relates to dating, numbering or other imprinting mechanisms used in connection with printing presses, numbering machines, etc., and is especially designed for use where two or more such mechanisms are employed in combination, one mechanism being changed in each cycle of operation of the press, while another is changed only once in the cycle of operation of the former mechanism, or at other predetermined intervals.

Heretofore the usual method of numbering and dating cards or envelops, for instance, has been to print as many as may be desired under a given date, the cards or envelops being consecutively numbered. This requires, where an allotment is to be made according to the numbers, that all the cards or envelops be subsequently collated so as to provide for each number cards or envelops for all the dates. For instance, in printing church envelops for weekly offerings, say on an order to supply three hundred persons, the printer will run out three hundred envelops all bearing the same date and numbered consecutively from 1 to 300. He then changes the date line and runs off another series of three hundred likewise numbered from 1 to 300. This is continued for fifty-two or fifty-three different dates. The envelops then have to be collated by hand, that is to say, there have to be three hundred piles or stacks each containing fifty-two or fifty-three envelops all bearing the same number but different dates.

The object of my invention as applied to the foregoing illustration is to change the date in each operation of the press while the number is only changed once in each cycle of operation of the dating mechanism, so that the full quota of envelops appropriate to each number is obtained without the necessity of collating at the completion of the printing operation. In other words, I propose to change one printing mechanism

(the dating) in each cycle of operation of the press, and the other printing mechanism (the numbering) at predetermined points or once in each cycle of operation of the dating mechanism. Similarly, by substituting numbering or other imprinting mechanism in place of the dating mechanism, it is possible to produce printed matter bearing two series of numbers, one number being changed at each impression and the other number only at predetermined intervals.

A further object of my present invention is to automatically prevent any change in the dating or numbering mechanisms in the event of the tripping of the printing press; and a further object is to provide simple and highly efficient means for attaining the objects hereinbefore recited.

In the accompanying drawings, Figure 1 is a fragmentary view of a printing press with my improvement applied thereto. Fig. 2 is a rear elevation, with parts broken away and others in section. Fig. 3 is a view in perspective of the mechanism for operating the numbering and dating attachments. Fig. 4 shows the numbering-mechanism controlling lever and the element by which it is operated once in each cycle of operation of the dating mechanism. Fig. 5 is a transverse sectional view on line 5—5, Fig. 2. Figs. 6 and 7 are rollers of the dating mechanism. Fig. 8 shows the members of one of the dating chain-links separated. Fig. 9 shows a slight modification. Fig. 10 shows means for operating both mechanisms in unison in each operation. Fig. 11 shows means whereby the numbering mechanism derives its motion from the dating mechanism.

Referring to the drawings, 1 designates the frame of a printing press, and 2 the impression cylinder mounted in eccentric bearings 3 which are connected to a spring-impelled throw-off shaft 4 after the manner employed in the well-known Harris press for which my present improvement is especially designed. When the impression is tripped shaft 4 is partly turned.

5 designates the dating mechanism and 6 the numbering mechanism. Both mechanisms are carried by a common shaft 7, suitably mounted and having a gear which meshes with the impression-cylinder gear. The dating mechanism consists of an endless series of type-carrying links pivotally

connected together and located below the printing surface except at a single point where one link at a time is designed to co-operate with the impression cylinder. Each 5 link has a base 8 which is provided with oppositely projecting apertured lugs 9, those of the several links overlapping and being pivotally connected together by pins 10. To the base 8 is secured a retaining plate 12, 10 the longitudinal edges of which are bent toward each other, and being of yielding material will securely hold the type-plate 13. The pins 10 connecting the several links convert the latter into a sprocket-chain, 15 said pins being designed to enter recesses 14 formed in peripheral enlargements of a series of rollers supported by a web 15 keyed on shaft 7. One of these rollers is adjustably mounted in a slot 16 20 of the web to enable the proper tension to be placed on the belt. By loosening this adjustable roller sufficiently the belt may be readily shifted back and forth with reference to the driving roller 17 so as to locate 25 the imprints in proper relation to the number changing mechanism. The roller 17 is carried by the belt-operating shaft 18, and being the roller by which the belt is supported at the time the imprint is made, it 30 has flat bearing surfaces to form firm seats for each link, as shown in Fig. 6.

The operating shaft 18 of the dating mechanism at its outer end has a pinion 19 which is partially rotated once in each cycle 35 of operation of the machine by the outward movement of the pawl-carrier 20 whose spring-pressed pawl 21 engages the pinion. The pawl-carrier, which is normally held retracted by a spring 22, is loosely journaled 40 on shaft 18 between the pinion and a casting 23 keyed on shaft 7. The pawl-carrier has an outwardly projecting lug 24 upon which is loosely mounted a roller 25. In each revolution of shaft 7 this roller will 45 engage a cam switch 26 pivotally hung within a fixed cam plate 27 and thereby the pawl-carrier will be moved outwardly to effect turning of the belt-operating shaft 18 to bring a new type-carrying link into position.

The actuating cam switch 26 is connected by an arm 28 and link 29 to throw-off shaft 4, so that in the event of the impression of 55 the printing press being tripped the cam switch will be moved out of its normal position to avoid actuating the pawl-carrier.

30 designates a spring-impelled retaining pawl pivotally mounted on casting 23, and held in engagement with pinion 19 to prevent back-lash.

50 The pinion 19 meshes with a gear wheel 31 to rotate it on shaft 7. This gear wheel is detachably secured to a disk 32, and is 65 preferably formed in two parts which may readily be removed, and replaced by a differ-

ent gear, so that the number of teeth may correspond with the number of links in the dating belt. This is of advantage where there are fifty-three date lines to be printed instead of the usual number, fifty-two. This 70 gear wheel 31 makes one complete revolution to one of the dating belt, and it, or more properly its disk 32, has a lug 33 which is designed to effect the actuation of the numbering mechanism 6 once in each cycle of 75 operation of the dating mechanism.

The numbering mechanism 6 comprises a numbering head mounted on shaft 7 and in the present instance is shown as supporting the dating mechanism actuating shaft 18, 80 although this is not essential. The pawl-carrier 33^a of the numbering head is connected by a link 33^b (see Fig. 9) to a shaft 34 which is supported in a bearing 35 as well as in spider 15 and casting 23. At its outer 85 end, adjacent this casting, the shaft 34 has an arm 36 which is engaged by a spring-pressed lever 37, which lever is fulcrumed on casting 23, and at its lower end carries a lug 38 which is normally in the path of lug 33. 90 Hence, according to the construction shown, the numbering head is changed only once in each revolution of gear wheel 31. It is obvious, however, that by additional lugs on the disk 32 the numbering heads may be 95 changed at predetermined points.

Fig. 9 shows a modification wherein the pinion 19 is replaced by or serves as a ratchet wheel 19^a, and the gear wheel 31 is replaced by a ratchet wheel 40 of sufficiently 100 smaller diameter not to be engaged by ratchet 19^a. The pawl-carrier 20 also carries an auxiliary pawl 41 which advances ratchet wheel 40 one tooth at each operation.

Fig. 10 shows a construction which may be used where it is desired to advance the numbering head at each actuation of the dating mechanism, or in other words, where both mechanisms are actuated at each revolution of the press. In this instance the pawl-carrier 20 has a lug 42 which is connected by a link 43 to the actuating shaft 34. 110

According to the construction shown in Fig. 11, the bracket 44 supported by shafts 18 and 34 has a lug 44^a on which is pivoted a lever 45 forked at one end to receive a pin of an arm 46 fixed on shaft 34. The other end of lever 45 carries a lug 47 located in the path of a projection 48 of the dating belt, so that once in each cycle of operation of the dating belt, this projection will engage the lug 47, which in turn, through its connections, will partially rotate shaft 34 and actuate the numbering pawl frame 33^a. From bracket 44 extends a short arm 49 which supports a spring 50 for restoring lever 45 to its normal position after being actuated by the projection 48 of the belt. By the use of additional projections 48 the numbering head 125 130

may be operated at any desired intervals with relation to the dating belt, and the number of links in the dating belt may be increased or decreased at will without the necessity of changing other parts of the mechanism.

The advantages of my present invention will be readily appreciated by those skilled in the art.

10 It will be noted that I have provided an extremely simple and highly efficient dating and numbering attachment for printing presses; that by changing the dates once in each cycle of operation of the attachment 15 and the numbering mechanism only once in each cycle of operation of the dating mechanism, the dating and numbering of cards or envelopes may be effected without requiring the time and care heretofore necessary. It 20 will also be observed that when the impression is tripped the actuating switch of the dating and numbering attachment will be thrown from its effective position.

Although the dating belt is constantly revolving it is capable of coöperating with the impression cylinder only at a single point; and by having the pins connecting the links engage the notches in the supporting rollers a very substantial construction is produced; 30 and also by changing the gear wheel of the actuating mechanism of the numbering attachment the same mechanism may be employed for printing a greater or lesser number of dates.

35 The type of construction illustrated by the accompanying drawings has particular reference to the numbering and dating of church envelopes while they are being printed, but it is to be understood that I do not 40 confine myself to this particular form of construction, and while the invention is herein shown as adapted to a rotary press, it is capable of adaptation to any style of press as well as to numbering machines, embossing presses, stamping presses, etc.

I claim as my invention:

1. In combination with a printing press, a printing mechanism comprising a plurality of printing members, a second printing mechanism also comprising a plurality of printing members, means for changing the arrangement of the members of said first mechanism in each cycle of operation of the press and for changing the arrangement of 50 the members of said second mechanism at a predetermined point in the cycle of operation of said first mechanism, and means for automatically preventing the operation of either mechanism in the event of any interruption in the feed supply.

2. In combination with a printing press, a plurality of separate and self-contained printing mechanisms each comprising a plurality of shiftable printing members, means for operating said mechanisms, means for

changing the arrangement of the members of one mechanism in each cycle of operation of the press and for changing the arrangement of the members of another mechanism at a predetermined point in the cycle of the former mechanism, and automatically operated means for preventing the operation of either mechanism in the event of any interruption in the feed supply.

3. In combination with a printing press, 75 a printing mechanism comprising a plurality of shiftable printing members, means for operating said mechanism, means for shifting the members of said mechanism at predetermined intervals, a second printing 80 mechanism also comprising a plurality of shiftable printing members, means for operating said mechanism, means controlled by the actuation of the former mechanism for shifting the members of the second mechanism at other predetermined intervals, and means for automatically preventing the operation of either mechanism in the event of 85 any interruption in the feed supply.

4. In combination with a printing press, 90 numbering mechanism and dating mechanism for coöperating with the press, means for rotating both mechanisms in synchronism with the press, and means for changing the dating and number mechanism, one being changed in each cycle of operation of the press and the other at predetermined 95 points in each cycle of operation of the former.

5. In combination with a printing press, 100 a plurality of separate printing mechanisms each comprising a plurality of changeable printing members, a shaft for changing one of said mechanisms, an auxiliary shaft connected to another of said mechanisms, and means connected to said first mentioned shaft for actuating said auxiliary shaft at predetermined intervals in the operation of said first mentioned shaft.

6. In combination with a printing press, 110 a plurality of separate printing mechanisms coöperating therewith, a shaft for operating one of said mechanisms, an auxiliary shaft connected to another of said mechanisms, 115 and means controlled by the actuation of said operating shaft for actuating the auxiliary shaft at predetermined intervals.

7. In combination with a printing press, 120 a plurality of separate changeable printing mechanisms, a plurality of shafts for changing said mechanisms, means for actuating one of said shafts in each cycle of operation of the press, and means controlled by said actuating means for actuating another of 125 said shafts at predetermined intervals.

8. In combination with a printing press, having an impression cylinder, a rotary shaft operable in synchronism with said cylinder, printing mechanism consisting of 130 an endless belt mounted on said shaft, means

- for advancing said belt once in each cycle of operation of said shaft, a second printing mechanism also carried by said shaft, means for actuating said second printing mechanism once in each cycle of operation of said belt, and means actuated by the actuation of the first mentioned mechanism for operating the actuating means of the second mentioned mechanism.
- 10 9. In combination with a printing press having an impression cylinder, a rotary shaft operable in synchronism with said cylinder, printing mechanism comprising an endless belt, a support for said belt carried by said shaft, an operating shaft for

said printing mechanism, means for actuating said operating shaft in each cycle of operation of the first-mentioned shaft, a pawl connected to said actuating means, and a wheel mounted on the first-mentioned 20 shaft and in mesh with said pawl, the number of teeth on said wheel corresponding with the number of type faces on said belt.

In testimony whereof, I have signed this specification in the presence of two subscribers.

CARL G. PRITCHARD.
